UNITED STATES PATENT OFFICE.

WILBUR R. THOMPSON, OF FRANKLIN TOWNSHIP, OWEN COUNTY, INDIANA, AS-
SIGNOR OF ONE-HALF TO ELMER P. WARREN, OF INDIANAPOLIS, INDIANA.

REMOVABLE BEAM BOTTOM FORM HANGER AND SPACER.

Application filed October 2, 1922. Serial No. 591,814.

To all whom it may concern:

Be it known that I, WILBUR R. THOMPSON, a citizen of the United States, residing in Franklin Township, in the county of Owen 6 and State of Indiana, have invented new and useful Removable Beam Bottom Form Hangers and Spacers, of which the following is a specification, reference being had to the accompanying drawings and to the letters 10 and figures of reference marked thereon.

This invention relates to the covering of metallic structural beams by molding concrete or other plastic protecting material thereon, and the invention has reference 15 more particularly to a hanger and spacer whereby to properly support a form bottom on the beam while molding the concrete.

An object of the invention is to provide a hanger which shall be so constructed as to 20 hang a molding form bottom on a metallic beam and permit the hanger to be readily removed for future use after concrete molded on the form bottom has become set.

Another object is to provide a hanger and 25 spacer of such construction as to be capable of being removably supported by a metallic beam and to support a bottom form on which side forms may be supported and spaced a proper distance away from the 30 beam.

A further object is to provide a removable beam bottom form hanger and spacer which 35 shall be so constructed as to be adapted to be quickly arranged for use and be a means for facilitating the work when covering a metallic beam with concrete or cement while the beam is in its place in a building structure, which hanger and spacer shall be reliable, durable and economical in use.

With the above-mentioned and other objects in view, the invention consists in a novel hanger rod having a novel head to be 40 removably supported on a wing or flange of a beam, the rod being provided with means 45 to support a bottom form and the head having a side guide against which to set a side mold form the required distance from the beam; and, the invention consists also further in the parts and combinations and arrangements of parts as hereinafter particularly described and further set forth in the 50 accompanying claims.

Referring to the drawings,—Figure 1 is a fragmentary perspective view of a mold form supported on a beam by the new hang-

er and spacer, and concrete molded on to the beam, to clearly illustrate and explain the particular purpose of the invention; Fig. 2 is a top plan of the hanger and spacer; Fig. 3 is a side view of the hanger and spacer; Fig. 4 is a front view of the hanger and spacer; and, Fig. 5 is a transverse section, partially broken away, of the structural I-beam and mold forms supported thereon by means of the new hanger and spacers 65 ready for the application of the covering substance.

Similar reference characters in the several figures of the drawings indicate corresponding or like elements or features of construction herein referred to in detail.

In the drawings the type of beam required to be covered is horizontally arranged and customarily supported at its ends, that usually used in the construction of the building being of I section having a web or vertical plate 1, lateral lower wings or flanges 2 and 3 and upper wings or flanges 4 and 5. In the operation of covering the beam a bottom portion form 6 provided with re-enforcing cleats 7 is supported at such distance as may be desired below the beam, and side forms 8 and 9 are set upon the bottom form at such distance as may be desired from the sides of the beam, enabling workmen to rapidly apply concrete 10 beneath the beam, side covering concrete 11 and 12 on opposite sides of the beam and top covering concrete 13 upon the top of the beam, the concrete being monolithic.

For the purpose of the present invention the bottom form 6 has bolt-holes 14 and 15 suitably spaced apart, these preferably extending to the cleats in which continuing holes 16 and 17 are bored to receive portions of the hanger and spacers.

Each hanger and spacer is composed of suitable metal and comprises a rod portion 18 designed to fit closely in a hole 14 or 15, the rod portion having a novel head thereon which extends from one side of the rod portion and is tapered generally to permit it to be readily withdrawn from the cement or concrete, the head having an under portion 19 of suitable length and having an end 105 or shoulder 20 designed to set against the edge of a lower wing or flange of the beam, the face of the portion 19 extending from the rod portion at an obtuse angle relatively thereto, the proportion being such that the

rod portion 18 extends vertically through the bottom form when the shoulder 20 is in contact with the wing of the beam. The head has a nose 21 that projects beyond the shoulder 20 and has a bottom face portion 22 designed to be supported upon the wing or flange of the beam. The head has a rear spacing portion 23 that is thicker than the rod portion 18 and extends partially along the rod portion and it has a straight guide face 24 that is parallel relatively to the rod portion, and its lower end constitutes a shoulder 25 against which the bottom form is secured so as to space the bottom form

15 the required distance below the beam. The head has an inclined or beveled top 26 that recedes from the guide face 24 towards the nose portion 21 which has a convexly curved top and end portion. The head has 20 also straight sides 27 and 28 that are convergent from the guide edge 24 to the nose portion, insuring easy withdrawal from the concrete.

25 The rod portion 18 of the hanger and spacer is provided with suitable means whereby to directly support the form bottom, the rod portion preferably having screw threads 29 extending from its end with which a nut 30 is connected, and if 30 desired the rod portion may also have a slot 31 therein in which a key 32 is inserted below the nut, and it will be understood that either the nut or the key in some cases be dispensed with.

35 In practical use a suitable number of the hanger and spacers are placed in the holes prepared for them in the bottom form and the heads are hung on the wings 2 and 3 in the manner described, the bottom form 40 being brought up to the shoulders 25, after which the side forms 8 and 9 are placed upon the bottom form and against the guide faces 24, the side forms being suitably secured in place as customary and may assist 45 in maintaining the shoulder 20 against the wings or flanges of the beam, the side forms thus being spaced the required distance apart from the beam. The forms having been properly set, the cement or concrete is 50 poured into the mold form and fills the space below the beam, the major portions of the hanger and spacers becoming embedded in the concrete. After the concrete or other plastic material that may have been utilized 55 has become properly set the side forms are removed, after which the bottom form is released and lowered away from the hanger devices, and the latter may be lightly tapped by any suitable instrument and will readily 60 become loosened from the concrete from which they may be taken and kept for future use.

Having thus described the invention, what is claimed as new is:

65 1. A removable beam bottom form hanger

including a rod portion and a tapered head on one side of the rod portion integral therewith adjacent to one end thereof, the head having a relatively narrow nose portion and a bearing face on the under side thereof extending from the end of the nose portion and a guide shoulder at the end of the bearing face, the shoulder facing away from the base of the head, the head having a straight spacer portion on the opposite side of the rod portion, the rod portion being provided adjacent to the opposite end thereof with a device to support the bottom form.

2. A beam bottom form hanger comprising a rod portion and a head portion on one end of the rod portion, the head portion extending laterally beyond one side of the rod portion and being tapered and having a guide shoulder at the under side thereof facing away from the base of the head, the head having a relatively thin and tapered nose portion extending beyond the guide shoulder for support upon a beam flange, the head portion extending also laterally beyond the opposite side of the rod portion and along the rod portion towards the opposite end thereof to constitute a spacing guide and a stop shoulder on the rod portion, and a device connected with the rod portion opposite to the stop shoulder to support the bottom form.

3. In a beam bottom form hanger, a hanger device comprising a rod having a head extending beyond one side thereof and provided with a spacing portion on the opposite side of the rod, the spacing portion having a straight guide face extending along the rod parallel thereto, the head being integral with the rod and being tapered from the guide face of the spacing portion to the end of the head to permit the device to be drawn from a cavity, in combination with a device to co-operate with the rod to support a bottom form.

4. The combination of a beam bottom form having holes spaced apart, a plurality of hanger and spacer devices having rod portions arranged in the holes respectively, each device having a head extending beyond one side thereof, the head having a guide shoulder on the under side thereof facing away from the rod portion, the head having a spacing portion on the opposite side of the rod portion that has a straight guide face parallel with the rod portion and the end of the spacing portion constituting a stop shoulder, and a supporting device on each one of said rod portions to support said bottom form.

5. The combination with a beam having lateral wings, a flat bottom form below the beam and having holes therein spaced apart a distance greater than the width of the beam and its wings, and vertical side forms

upon the bottom form spaced apart from opposite sides of the beam and set outward beyond said holes, of a plurality of hanger and spacer devices having tapered heads, supported upon said wings and extending reversely to and vertically guiding the side forms, the heads having long guide faces bearing against the sides of the side forms

and having also guide shoulders engaging the edges of said wings, said devices having 10 rod portions extending through said holes, and means cooperating with the rod portion and supporting the bottom form.

In testimony whereof, I affix my signature on the 26 day of September, 1922.

WILBUR R. THOMPSON.
